UNITED STATES PATENT OFFICE.

WILLIAM LOUIS BESSOLO, OF SAN DIEGO, CALIFORNIA.

DESIGN FOR A WRENCH.

50,119.

Specification for Design.

Patented Jan. 2, 1917.

Application filed August 16, 1916. Serial No. 115,300. Term of patent 14 years.

To all whom it may concern:

Be it known that I, WILLIAM L. BESSOLO, a citizen of the United States, residing at San Diego, in the county of San Diego and State of California, have invented a new, original, and ornamental Design for Wrenches, of which the following is a specification, reference being had to the accompanying drawing, forming part thereof.

The figure in the drawing is a perspective view of a wrench showing my new design.

I claim:

The ornamental design for a wrench as shown.

WILLIAM LOUIS BESSOLO.
